(57) **CLAIM**

The ornamental design for a foot file, as shown and described.

DESCRIPTION

FIG. 1 is a front, left and bottom perspective view of a foot file, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an exploded perspective view showing the order of assembly with a cover feature drawn in broken lines that is not claimed;

FIG. 10 is an enlarged detail view of area 10 of FIG. 1 thereof; and,

FIG. 11 is an enlarged detail view of area 11 of FIG. 1 thereof.

The dash-dash broken lines shown in the drawings illustrate portions of the foot file that form no part of the claimed design. The dot-dash broken lines illustrate the boundaries of the enlarged detail views and form no part of the claimed design.
